UNITED STATES PATENT OFFICE.

PETER BORN, OF NEW YORK, N. Y.

SOFA-FRAME.

Specification of Letters Patent No. 22,619, dated January 18, 1859.

To all whom it may concern:

Be it known that I, PETER BORN, of the city, county, and State of New York, have invented a certain new and useful Mode of 5 Forming Frames for Sofas, Chairs, &c.; and I do hereby declare that the following is a full, clear, and exact description of the same, reference being had to the annexed drawings, making a part of this specification, in 10 which—

Figure 1, represents a plan or top view of the form which I use for forming the frame of a sofa. Fig. 2, is a vertical transverse section of the same, the line α, α , Fig. 1, indicating the plane of section.

Similar letters of reference indicate corresponding parts in the two figures.

This invention consists in constructing a form of wood in such a manner, that the 20 complete frame of a sofa may be pressed and formed over it, so that the same, with the back and legs attached, is of uniform strength and thickness throughout, showing no visible joint; said form being constructed of a number of parts which are united by clamps fitting over dovetailed projections so that the same may be removed when the frame has been finished and that it may be used over and over again for 30 forming a number of frames of the same character.

To enable others skilled in the art to fully understand and use my improvement, I will proceed to describe it.

35 A, is a form, the shape of which is such that a piece of wood pressed over the same forms the frame of a sofa. This form consists of four parts, B, C, D, and E, which are united by a number of clamps F, fitting 40 over dovetailed projections α . In dividing this form, great care must be taken so that the planes of the sections are not parallel, but they ought to converge inwardly so that the several parts may be easily removed after the frame has been finished.

In order to form the frame I first glue a piece of paper on the outside of the form so that the form when finished, may be separated from the same without injury to 50 either. I then glue thin layers of wood, such as veneers, on the form, one on the top of another and in such order that the joints

of a subsequent layer do not coincide with the joints of the preceding one so that no joint is visible when the required thickness 55 has been reached, and when the frame is complete, it is of uniform thickness and strength throughout. The red lines in Fig. 2, indicate the manner in which the layers of wood are placed on the form and after 60 the frame has been finished, the clamps F, are withdrawn and the several parts of the form are removed, one after the other. It will be noticed that it will be quite easy to remove the two parts D, and E, but great 65 care must be taken in removing the two parts B, and C, and it can be done by first depressing the part B, and withdrawing the same from the frame carefully. The last part, C, may be easily taken out and the 70 several parts are now united again and another frame is commenced over the same form and in the same way.

The form may be constructed of any thickness whatever provided the surface of 75 the same corresponds to the required shape of the frame, and it can therefore be made as durable as desired, so that any number of frames may be formed over the same and so that these frames may be finished to a 80 certain extent while they are on the forms, as they are less liable to get injured as long as they are supported by the latter.

It is obvious that the frame of a chair or 85 table or in fact any other frame of a similar kind may be formed over such forms in the same manner, but this mode is of particular advantage for sofas, and arm-chairs and other more complicated frames, which are usually made out of a number of parts jointed and fitted together whereby the strength 90 of the same is materially impaired. On the other hand my frames have no visible joints and they are of uniform strength and thickness throughout.

I am well aware that parts of frames, such 95 as chair backs or the sides of a bedstead have been formed in a similar manner long ago, by pressing and gluing a number of veneers over a suitable block of wood, the 100 surface of which is brought to the required shape, therefore I do not claim, broadly, the manner of pressing wood over a form, but, to the best of my knowledge and belief, a

UNITED STATES PATENT OFFICE.

J. J. H. BRIANCHON, OF PARIS, FRANCE.

IMPROVEMENT IN COMPOSITIONS FOR ORNAMENTING GLASS.

Specification forming part of Letters Patent No. 22,620, dated January 18, 1859.

To all whom it may concern:

Be it known that I, JULES JOSEPH HENRI BRIANCHON, of Paris, in the Empire of France, have invented certain Improvements in Coloring and Ornamenting Glass, Porcelain, Earthenware, and other Ceramic Substances; and I do hereby declare that the following is a full, clear, and exact description of the same.

My invention has for its object to impart to ceramic substances the color of gold, white and colored mother-of-pearl, the variegated and changing reflections of shells, of all kinds of minerals, and of the optical prism.

It consists in the preparation and use of chemical products which particularly apply to English china-ware, porcelain, earthenware, glass, and crystal ware of all sorts. These products cause these ceramic substances, when submitted (according to their nature) to the heat of a suitable furnace or oven, to that of a muffle-furnace, or it may be to a less heat, to possess a splendor and metallic brilliancy comparable to that of mirrors, and of such solidity that the colors have the appearance of being under enamel. The chemical products, composed principally of carburets of hydrogen and of metallic salts, are used to coat the ceramic substances on glazings or varnish, and serve to form thereon the groundwork and the decorations of all sorts. The process by the aid of which I obtain these results is divided into two parts, first, the preparation of the fluxes; second, the preparation of the coloring-matters. These latter, once obtained, are added in variable proportions to the fluxes, and thus produce a great variety of tints. The fluxes which serve to glaze metallic salts and oxides are salts of bismuth and of lead. The first are preferable, as they undergo high temperatures much better than the others, and without altering. Their preparation to serve for fluxes is the same. I take ten parts (in weight) of nitrate of bismuth, thirty parts of resin, and seventy-five parts of essence of lavender, or any other essence which does not cause any precipitation in the mixture, with which I proceed as follows:

I put the thirty parts of resin into a capsule resting in a bath of sand, heated gradually, and in proportion as it melts I pour in the ten parts of nitrate of bismuth, a little at a time, and stir it continually, in order to incorporate

the two substances. As soon as and according as the mixture begins to brown I pour in forty parts of the essence of lavender, and continue to agitate the whole, in order to make these substances mix well together, and to obtain a solution of them. The capsule is then withdrawn from its sand bath and gradually cooled. It is then that the remaining thirty-five parts of essence of lavender are added, and after which the whole is allowed to cool for some hours. The metallic salts and oxides which assist in forming the coloring-matters are salts of platina, silver, palladium, rhodium, iridium, antimony, tin, uranium, zinc, cobalt, chrome, copper, iron, nickel, manganese, &c., and sometimes salts of gold also, in order to produce in the latter case either the rich tints of shells or the reflections of the prism.

The coloring-matters are thus obtained:

First coloring-matter, yellow.—Thirty parts of common resin are dissolved in a capsule heated by a bath of sand. When the common resin is on the point of melting ten parts of nitrate of uranium are added, and while stirring I add from thirty-five to forty parts of essence of lavender. When the liquid matter has been rendered suitably homogeneous by stirring the capsule is withdrawn from the fire, and from thirty to thirty-five parts of essence of lavender are again added. This coloring-matter, mixed in equal parts with the flux of bismuth, and applied on the object with a brush, furnishes a preparation which, after baking, gives a brilliant yellow tint.

Second coloring-matter, orange-red.—It is made by melting fifteen parts of common resin, and adding, after fusion, fifteen parts of nitrate of iron and eighteen parts of essence of lavender at the same time. These additions are made by a little at a time, taking care to stir it. On the mixture becoming homogeneous it is withdrawn from the fire, and as soon as it is a little cooled twenty parts of essence of lavender are added. This coloring-matter, mixed with the flux in proportions equal to two-fifths or one-third or other intermediate proportions of its weight, furnishes a preparation which, after baking, gives a red orange or nankin color, and all the intermediate tints according to the proportions of flux employed.

Third coloring-matter, imitation of gold.—It is made by mixing the two preparations indi-

cated above, putting two or three parts of the preparation of uranium for one part of preparation of iron. It is by mixing the two preparations that a metallic color is produced which, after baking, imitates the various tints of polished gold.

Fourth coloring-matter, variegated colors of the prism.—Ammoniuret or cyanuret of gold, and of mercury, or ioduret of gold, or gold-dye is added. These auriferous compositions, mixed with essence of turpentine, are pounded on a palette so as to form a paste, which is allowed to dry, in order to be repounded when mixed with essence of lavender. This done, one, two, three, and up to ten, parts of flux prepared with bismuth are added to one part of the auriferous product. By spreading it with a brush on the molded and baked paste and by covering it with solution of uranium darker or lighter and more or less variegated tints are obtained.

All these preparations mix well together. They can also be applied the one above the other, and when so applied with a brush on the objects they always furnish, after baking, varied colors and shades.

Mother-of-pearl tints are more easily obtained on crystal and on glass than on chinaware. For this purpose the flux of bismuth is mixed with flux of lead, and sometimes chloride of antimony mixed in resin is added.

The essence of lavender employed in all the preparations may be replaced by any other essence which does not precipitate substances

with which it may be mixed. In the same way the common resin may be replaced by colophony or any other resin.

In the application of the preparations, which is done with a brush, care should be taken to avoid laying them on in too thin or too thick coats, which would produce too pale or too dark tints. It is important that dust be prevented from accumulating on the coated objects.

I claim—

The yellow coloring, composed of resin, nitrate of uranium, essence of lavender, and the flux of bismuth; also, the orange-red coloring, composed of resin, nitrate of iron, essence of lavender, and the flux of bismuth; also, the imitation-gold coloring, composed of the above-described orange-red coloring and the yellow coloring, mixed together, with additional parts of the preparation of uranium and iron; also, the variegated prismatic coloring, composed of ammoniuret or cyanuret of gold, or gold-dye, turpentine, essence of lavender, the bismuth flux, and uranium; also, the mother-of-pearl coloring, composed of the bismuth flux, the flux of lead, chloride of antimony, resin, lavender or other essence, and colophony, all of the above colorings being made and applied in the manner and in proportions substantially as herein set forth.

J. J. H. BRIANCHON.
